UNITED STATES PATENT OFFICE.

GEORGE FRANCIS STANFIELD, OF NEW ORLEANS, LOUISIANA.

WHIP-SOCKET.

No. 906,324.

Specification of Letters Patent.

Patented Dec. 8, 1908.

Application filed March 28, 1908. Serial No. 423,887.

To all whom it may concern:

Be it known that I, GEORGE FRANCIS STANFIELD, a citizen of the United States, and a resident of New Orleans, in the parish 5 of Orleans and State of Louisiana, have invented a new and Improved Whip-Socket, of which the following is a full, clear, and exact description.

The purpose of this invention is to provide 10 novel details of construction for a whip socket, which afford a neat strong, simple and inexpensive device of the character indicated that will securely hold the stock of a whip, avoid injury thereto and which permits the release of a whip from the socket by foot pressure.

The invention consists in the novel construction and combination of parts, as is hereinafter described and defined in the appended claims.

Reference is to be had to the accompanying drawings forming a part of this specification, in which similar characters of reference indicate corresponding parts in all 25 the views.

Figure 1 is a side view of the improved whip socket, secured in position for service on a dash board of a vehicle, a partial edge view of the dashboard only being shown; 30 Fig. 2 is a longitudinal sectional view of the whip socket, taken through the axis and shown on a portion of a dashboard; and Fig. 3 is a transverse sectional view, substantially on the line 3—3 in Fig. 2.

In the drawings that illustrate the construction and application of the improvement for service, it will be seen that the whip socket consists of two principal parts or sections 5, 6, that coöperate for the support and retention of a whip stock until designedly released. The section 5, as indicated in Fig. 1, consists of two integral members 5^a, 5^b, each member being concaved on one side and convexed on the other 45 side, thus producing two substantially similar straight walls that are virtually portions of a cylindrical tube. At adjacent ends, the members 5^a, 5^b, are connected by two oppositely disposed and diagonally trending web walls *a*, *a*, that have such a length and diagonal inclination as serves to dispose said members suitably spaced apart in parallel planes with their concave surfaces innermost, thus rendering them in effect fragmentary walls of a tube.

Two similar forked bracket arms 7, 7, are

secured upon the exterior of the member 5^a, respectively near the upper and lower portions thereof, said arms being furnished at their opposite ends with the base flanges 7^a, 60 which are secured upon a dashboard A, as indicated in the drawings and thus hold the socket section 5 in an erect position.

The socket section 6 is formed with two members 6^a, 6^b, that are substantially similar to the members 5^a, 5^b, of the fixed section 5, these members being integrally connected together at contiguous ends by two oppositely disposed web walls *b*, *b*, that are nearly similar to the web walls *a*, *a*. 70

The web walls *b*, *b*, are so spaced apart that the socket section 6 may be slid over the socket section 5 and the web walls *b*, *b*, be crossed and lapped upon the exterior surfaces of the web walls *a*, *a*, whereon they 75 are centrally pivoted, as shown at *c*, *c*, in Figs. 1 and 2, thereby supporting the socket section 6 on the fixed section 5.

The members 6^a, 6^b, are disposed directly opposite the sections 5^a, 5^b, respectively, and 80 said sections in pairs, form the socket walls of a nearly cylindrical shape that may be diverged at their upper and lower ends by rocking the section 6 on the fixed section 5.

The socket members 5^a, 6^a, have their 85 concavo-convex walls flared outwardly at their upper ends, thus producing an enlarged entrance or throat *d* that facilitates the insertion of a whip stock into the socket. The lower member 6^b of the socket section 6, is 90 extended down a proper distance below the lower end of the socket member 5^a, and the lower portion of the section 6^b is extended forwardly so as to project below the lower extremity of the socket member 5^b, affording 95 a foot flange 6^c that is preferably concaved on its upper side, and at its free end 6^d, extends a short distance in front of the socket member 5^b. Upon the exterior of the socket member 5^a, is secured the upper portion of a 100 plate spring 8, which extends downward at its free end, and with proper resilience, presses upon the exterior surface of the socket member 6^b, thus normally disposing this socket member substantially parallel 105 with the socket member 5^b.

The interior diameter of the complete whip socket, is so proportioned that the handle portion A' of a whip A² may be readily introduced between the flared upper 110 ends of the socket members 5^a, 6^a, and subsequently pressed down between the fixed

and rockable sections of the socket until said handle at its lower end, is seated upon the foot flange 6^c.

The free outer end 6^a of the foot flange 6^c, is spaced a suitable distance from the lower extremity of the socket member 5^b, which will permit the knob g on the lower end of the whip stock or handle A' thereof, to be pressed outwardly and below the lower edge 10 of the socket member 5^b, and it will be seen that by the impingement of the knob g, that is ordinarily placed on the end of a whip stock, the whip will be retained in the socket, due to the pressure of the spring 8 15 on the socket member 6^b.

The position of the whip socket on the dashboard A, is preferably at the right side of the latter, and such a distance above the floor of the vehicle, not shown, that the 20 driver may conveniently press the toe of his foot upon the free end 6^a of the foot flange 6^c when the whip is to be removed from the socket. This foot pressure will rock the socket section 6 on the fixed section 5 there- 25 of and release the whip by a divergence of the socket members 6^a, 6^b, from the mating socket members 5^a, 5^b, so that the whip may be simultaneously removed from the socket and after use be replaced in the socket by its 30 downward insertion thereinto, as before explained.

Having thus described my invention, I claim as new and desire to secure by Letters Patent:

- 35 1. A whip socket, comprising a fixed section, embodying two offset members having concavo-convex walls, a similar socket section rockably mounted upon the fixed section, a foot flange on the lower end of the 40 rockable section projected below and spaced from the lower end of the fixed section, and means for normally pressing the lower portion of the rockable section toward the fixed section.
- 45 2. A whip socket, comprising a fixed section formed of two members having concavo-convex walls, spaced apart by two diagonally disposed web walls, a similar section

having two spaced diagonally disposed web walls which cross and embrace the other web 50 walls, a pivot connection between each pair of web walls, a foot flange on the lower portion of the rockable section projecting below and spaced from the lower end of the fixed section, and a spring adapted for engagement with the lower portion of the 55 rockable section.

3. A whip socket, comprising a section formed of two similar members, having concavo-convex walls, two integral web walls 60 diagonally and oppositely disposed between the adjacent ends of said socket members, thus offsetting one member from the other, two bracket arms projected laterally from the upper member of the socket section for 65 attachment upon a dashboard, a nearly similar rockable socket section formed of two members having concavo-convex walls, integral diagonally trending web walls upon the adjacent ends of these socket members, 70 which web walls cross and lap upon the other web walls, a pivot between each pair of web walls at their centers, said pivots being disposed oppositely, a foot flange on the lower end of the rockable section projected 75 below and spaced from the lower end of the fixed socket section, and a plate spring mounted upon the upper member of the fixed section and pressing upon the lower member of the rockable section.

4. A whip socket comprising a fixed section, and a movable section crossing the fixed section and pivoted thereto a spring acting normally to move the movable section toward the fixed section, the lower end 85 of the movable section being extended to form a rest for the whip, and for engagement by the foot to swing the movable section.

In testimony whereof I have signed my 90 name to this specification in the presence of two subscribing witnesses.

GEORGE FRANCIS STANFIELD.
